CLAIM

We claim, the ornamental design for a body portion of a lamp, as shown and described.

DESCRIPTION

FIG. 1 is a first perspective view of an exemplary embodiment of the invention;

FIG. 2 is a second perspective view of the exemplary embodiment of FIG. 1;

FIG. 3 is a side plan view of the exemplary embodiment of FIG. 1, the body portion of a lamp being symmetric about a center axis;

FIG. 4 is a top plan view of the exemplary embodiment of FIG. 1; and,

FIG. 5 is a bottom plan view of the exemplary embodiment of FIG. 1.

The phantom lines shown in FIG. 1-FIG. 5 are environmental and not part of the claimed design.

The color of the body portion of a lamp forms no part of the claimed design, a body portion of a lamp according to the claimed design may be of any color or combination of colors. The shading and tones, and any variations thereof, shown in the figures do not imply any specific colors or color contrast scheme in the claimed design.

The surface treatment of the body portion of a lamp shown in the figures forms no part of the claimed design, a body portion of a lamp according to the claimed design may have any surface treatment.

References to "side", "top", and "bottom" in the figure descriptions are not meant to require certain in-use orientation, a body portion of a lamp according to the claimed design may be used in any orientation.
